FLAIL MOWER ATTACHMENT FOR A TRACTOR OR THE LIKE

Gail R. Sutherland, Ottumwa, Iowa, assignor to Deere
& Company, Moline, Ill., a corporation of Delaware

Filed Mar. 31, 1960, Ser. No. 59,980

Term of patent 14 years

(Cl. D40—1)

FIG. 1

FIG. 2

FIG. 4

Fig. 1 is a rear perspective view taken from the right side of a flail mower attachment for a tractor or the like embodying my new design;

Fig. 2 is a rear perspective view taken from the left side thereof;

Fig. 3 is a front perspective view taken from the top and left side thereof; and

Fig. 4 is another front perspective view thereof.

I claim:

The ornamental design for a flail mower attachment for a tractor or the like, substantially as shown.
